STOVE SYSTEM FOR BLAST FURNACES

Charles G. Bigelow, Arthur J. Whitcomb, and Arnold J. Karsten, Pittsburgh, Pa., assignors to Koppers Company Inc., a corporation of Delaware

Filed June 27, 1958, Ser. No. 744,952

16 Claims. (Cl. 251—81)

This invention relates to stove systems employed in blast furnace installations and more particularly to the control employed therein and the mechanism for actuating the valves.

The stove valves employed in a blast furnace stove system are commonly designated in accordance with their function and are known as hot blast, cold blast, gas shut-off, gas burner shut-off, blow-off, mixer selector, and chimney valves. The operation of these valves controls the inflow of gas and the outflow of flue gas to heat the stoves and the inflow and outflow of the air blast through the stoves to the blast furnace. Because of the size and weight of these valves, each valve is actuated by a separate power driving means such as an electrical motor. The valves are individually operated in accordance with the demands of the stove system and blast furnace. In some blast furnace installations there may be provided a central control station which is operative to selectively control the energization and de-energization of each of the valve motor actuators so as to control the movement of the valves.

In these prior hot stove systems difficulties have been encountered in achieving trouble-free operation. These difficulties have been caused primarily by the failure of the valves to function properly. These malfunctions can be traced to overload or overtravel of the motor or valve. For example, overloading often times occurs when the movable element of the valve is jammed within the valve body because of the presence of foreign material or a tight stuffing box or because the valve gate or disc comes against a mechanical stop at the end of valve travel in the closed position in order to assure tight closure of the valve. Under these conditions, when the motor is energized to move the valve, if the load is in excess of the stalling torque of the motor, the motor may burn out or if the movable element becomes free upon continued applications of the motor power, it may be abruptly moved such that damage results to the valve itself.

Also in these prior systems, if the power to the motors is not cut off promptly when the movable member arrives at its open or closed positions, the inertia of the motor and the moving valve member is such that the valve member jars to a sudden stop at its limit of movement causing excessive stresses which often result in damage to either the valve or motor drive mechanism.

It is an object of the present invention to provide a blast furnace stove system with an improved valve operating means.

It is a further object to provide an improved stove valve actuating arrangement incorporating therein a means for disconnecting the valve driving means from the motor in the event loads exceeding the stalling torque of the motor are encountered as in opening or closing the valve.

It is still another object to provide an improved stove valve actuating arrangement including an improved con-

2

trol circuit for starting and stopping the motor to move the valve from one position to another.

It is another object to provide an improved stove valve actuating arrangement including a two-speed motor and an improved control circuit for operating the same.

A feature of the invention is the provision in the valve control circuit of a time delay circuit which is effective for a predetermined interval of time after the valve member has reached its limit of travel so as to ensure 10 a positive opening or closing of the valve.

Generally, the invention is accomplished by providing each of the valves of a blast furnace stove system with an actuating mechanism comprising an electric motor which is mechanically coupled to the valve by the means 15 of a fluid coupling, speed reducer, and a mechanical linkage. To control the energization of the motor there is provided an electrical control system.

Further objects and features will hereinafter appear.

Fig. 1 is a schematic representation of a blast furnace 20 stove valve and an arrangement embodying the invention for actuating the valve.

Fig. 2 is a schematic wiring diagram of a control circuit for operating a single-speed motor used to drive the valve members.

Fig. 3a is a schematic wiring diagram of a circuit for operating a two-speed motor used to drive the valve member.

Fig. 3b is a schematic wiring diagram of the control circuit for operating the two-speed motor of Fig. 3a.

Fig. 4 is a graph illustrating the torque characteristics of the motor and the fluid coupling at various speeds.

Referring now to Fig. 1, there is schematically illustrated a stove main of a blast furnace stove system embodying the present invention. The numeral 11 designates a valve, such as hot blast, cold blast, gas shut-off, gas burner shut-off, blow-off, mixer selector, or chimney valve, located in the main 10 between the inlet end 11a and outlet end 12 thereof to control the passage of air or gas therethrough. The valve 11 is operated in accordance with the demands of the stove and blast furnace and includes a valve member 13 movably mounted to travel a predetermined distance t between a closed position c , in which position it is seated within a valve seat 14, to an open position o in which position the air or

40 gas flows through the port 15. The valve members 13 used in the blast furnace stove systems each generally weigh from 500 to 2000 pounds and a considerable force must be applied to move the valve member between its open and closed positions. In most cases, a counterweight (not shown) is connected to the valve member 11 in such a way as to counterbalance the weight of the valve member and make it operate easier.

45 To actuate the valve 13 between its open and closed positions o and c , there is connected thereto an actuating mechanism generally designated by the numeral 16. The actuating mechanism comprises an electric motor 17 connected by a motor driven shaft 18 to the input side 19 of a fluid coupling 20 of which the output side 21 is connected to the driving shaft 21-a of a speed reduction

50 unit 22 having an output shaft 23 connected to a mechanical linkage 24 which is operatively connected to the valve member 13.

The mechanical linkage 24 is usually of the type which 55 imparts a mechanical advantage for moving the valve member 13, such as for example by a crank, gear and pinion, or a pulley arrangement. The type of mechanical linkage used may vary in accordance with the structural characteristics of the valve. For example, in a hot blast valve it is preferred to use a cable and pulley arrangement, while in a gas burner shut-off valve, it is preferred to use a gear and pinion drive. It is to be under-

70

stood, of course, that in the event the characteristics of the valve are such that a mechanical linkage is not required, it may be omitted and the output shaft 23 may be connected directly to the valve member 13.

Mechanically connected to and driven by the speed reducer 22 is the cam type limit switch 154 in which there are cam switches later described in Fig. 2 as 156 and 176 and in Fig. 3b as 280, 282, 284-a, and 286, which are used in conjunction with the control system 100 to govern the speed and stopping of the valve member 13.

Connected to the input shaft 21-a of the gear reduction unit 22 by way of the shaft 21-a is the output end 21 of the fluid coupling 20 of which the other end 19 is connected to the driving shaft 18 of the motor 17. The fluid coupling may be similar to the type manufactured by the Twin Disc Clutch Company of Rockford, Illinois.

The fluid coupling 20 is selected of such a size that it will transmit less than the pull-out or stalling torque of the motor 17 when running at a motor speed approximately the speed at which the motor stalling torque occurs. This relationship is shown in Fig. 4 wherein the curve *a* represents the percentages of torque transmitted by the fluid coupling at various percentages of synchronous speed of the motor and the curve *b* represents the percentages of torque developed by the motor. Preferably this coupling size is such that the fluid coupling will be unable to transmit full motor torque until the speed of the driver end of the coupling is approximately 65% of the synchronous speed of the motor. Below 65% of the synchronous speed of the motor should the valve become jammed, the slip will be at 100% and the coupling will be transmitting less than full motor torque. Normally as the speed of the motor 17 and the disc 19 increases, the starting torque exerted on the member 21 correspondingly increases until the motor and member 21 reach relative speeds at which the torque required to drive the load is developed. During this time the slip increases and the torque applied on the valve member 13 correspondingly increases. This assures a shockless and cushioned start of the valve driving mechanism.

In the event that there is excessive load from stuffing box friction, or the valve disc 13 reaches a mechanical stop at the end of valve travel, the torque required to move the valve disc 13 will exceed the pull-out or stalling torque of the motor with the result that the motor speed and the fluid coupling speed will be decreased and as a result, the torque output of the fluid coupling 20 will not exceed its safe design value. This design value must be small enough to prevent damage to whatever mechanism is providing the abnormal resistance.

As further explanation of this action, reduction in speed of the fluid coupling increases the slip in the fluid coupling if the torque is assumed to remain the same. When the speed drops to approximately 65% of the synchronous speed of the motor, there will be 100% slip on the part of the fluid coupling 20 and the driven end 21 of the coupling will be at a standstill while the motor 17 continues to rotate. As a result of this action, the driven end or the valve member 13 is brought to a sudden stop which is cushioned with no shock or severe overload on the motor or the valve driving mechanism.

In carrying out the invention, either a single-speed or a two-speed motor may be used depending on the structural characteristics of the valve. For example, in the operation of a typical hot blast valve, it has been found preferable to use a two-speed motor and in a typical burner shut-off valve, to use a single-speed motor.

Referring now to Fig. 2, there is illustrated a single-speed conventional induction motor 17 having three terminals. Connected to the terminals 101, 102, and 103 are leads 104, 105, and 106, respectively, which are connected to a suitable source of three-phase alternating current by way of power leads 107, 108, and 109. A directional contactor RO controls the operation of the motor in a clockwise direction and a directional contactor RC con-

trols the operation of the motor in a counter clockwise direction.

Considering first the clockwise rotation, upon energization of the clockwise solenoid 112, which is a part of the contactor RO, the three armatures 113, 115, and 117 move downwardly to engage the contacts 114, 116, and 118, respectively, thereby connecting the lead 107 to lead 104, lead 108 to lead 105, and lead 109 to lead 106. Thus, the motor rotates clockwise so as to move the valve member 13 from its closed to its open position. Upon de-energization of the clockwise solenoid 112 of contactor RO, the armatures 113, 115, and 117 move out of contact with their respective contacts 114, 116, and 118 so as to de-energize the motor.

15 Energization of the counter clockwise solenoid 120, which is a part of contactor RC, causes three armatures 121, 123, and 125 to move downwardly to engage the contacts 122, 124, and 126, respectively, thereby connecting the lead 107 to lead 105 by way of leads 127 and 20 128, the lead 108 to lead 104 by way of leads 129 and 130, and the lead 109 to lead 106 by way of leads 131 and 132. In this manner, the phases of the power supply to the motor are reversed thereby causing the motor to rotate in a counter clockwise direction and close the valve. 25 Upon de-energization of the counter clockwise solenoid 120, the armatures 121, 123, and 125 move to the positions shown, de-energizing the motor 17.

The operation of the clockwise and counter clockwise directional contactors RO and RC are controlled by a 30 motor control system generally designated as VM.

The control system VM is energized by the secondary winding of the step-down transformer 134 of which the primary 135 is connected to leads 108 and 109. Upon closing of the master switches 136, the excitation of the 35 secondary winding 133 causes the terminals 137 and 138 to become energized. Connected in parallel to terminals 137 and 138 is a control circuit generally designated as VO for rotating the motor clockwise to open the valve and a second control circuit generally designated as VC for 40 rotating the motor counter clockwise to close the valve.

For rotating the motor clockwise and closing the valve, control circuit VO is energized.

When the selector switch 140 is in engagement with contact 140-a, the circuit VO will be governed by the 45 master control system (not shown) by means of the armature 141. When armature 141 is engaged with contact 142, a circuit is completed to energize clockwise solenoid 112 of contactor RO from terminal 137 by way of lead 144, lead 143, contact 142, armature 141, contact 140-a, 50 selector switch 140, normally-closed armature 139, contact 139-a, through the solenoid 112 to terminal 138. The master control system, not shown, is usually located in a central location in the blast furnace installation and includes the electrical circuitry for controlling the operation, sequencing, and interlocking of all of the valves of 55 the hot blast stove system.

Manual operation of the solenoid 112 of the directional contactor RO is effected by positioning the switch 149 in engagement with the terminal 145 and depressing the 60 push button 146-a into engagement with the contacts 147 and 146 such that it connects the lines 148 and 149. The line 148 is connected to contact 145 while the line 149 is connected to the terminal 137.

When the valve member 13 reaches its predetermined 65 open position *o*, there is operatively associated with the motor 17, by way of the speed reduction unit 22, a cam type limit switch mechanism 154 including a shaft 75 carrying a cam 155 which is set to move the switch 156 into engagement with the contact 157 when the valve reaches its open position *o*. Closing of the switch 156 connects the contact 157 to one end of the valve opening limit solenoid 161 to the terminal 137 by way of the lines 158 and 159 thereby to energize the valve opening limit solenoid 161 which is connected to the terminal 138 70 by way of the line 160. When the valve opening limit 75

solenoid 161 is energized, it pulls the normally closed valve opening limit armature 139 out of engagement with the contact 139-a thereby de-energizing the clockwise solenoid 112 of the directional contactor RO and opens the armatures 113, 115, and 117 to de-energize the motor 17.

For rotating the motor counter clockwise and closing the valve, control circuit VC is energized.

When the selector switch 165 is in engagement with contact 166, the circuit VC will be governed by the master control system (not shown) by means of the armature 167. When armature 167 is in engagement with contact 168, a circuit is completed to energize counter clockwise solenoid 120 of contactor RC from terminal 137 by way of leads 159 and 170, contact 168, armature 167, lead 169, contact 166, selector switch 165, lead 164, normally closed armature 162, through the counter clockwise solenoid 120 of contactor RC through lead 120-a to terminal 138. In this connection, it is to be noted that the master control system may incorporate interlocking means to prevent the simultaneous closing of the armatures 141, the circuit VO, and the armature 167 of the circuit VC. By using such interlocking means, the contactors RO and RC cannot be operated at the same time.

Manual operation of the circuit to energize the solenoid 120 of the directional contactor RC is effected when the selector switch 165 engages the terminal 171 and the push button 172 is depressed into engagement with the contacts 173 and 174, thereby completing a circuit from the solenoid 120 to the terminal 137 by way of lead 159, the contact 174, the pushbutton 172, the contact 173, lead 171-a, contact 171, selector switch 165, lead 164, normally closed armature 162, contact 163, through solenoid 120, through lead 120-a to terminal 138.

When the valve member 13 reaches its predetermined closed position c, a cam 175 on the cam type limit switch mechanism 154 is set to move the limit switch 176 into engagement with the contact 177 thereby to connect one end of the close limit solenoid 178 of a close limit relay having a normally closed armature 162 to terminal 137 by way of lines 159. The other end of the close limit solenoid 178 is connected to the terminal 138 by way of the lead 178-a. Hence, when the limit switch 176 is closed, the close limit solenoid 178 is energized thereby to move the armature 162 out of engagement with the contact 163. In this manner, the circuit to the counter clockwise solenoid 120 of the directional contactor RC is de-energized, and its armatures 121, 123, and 125 open, and the motor 17 is de-energized.

In Figs. 3a and 3b, there is shown a two-speed motor 17' for actuating the valve operation. While the motor 17' may be of any conventional two-speed type such as a squirrel cage induction motor having taps for varying the fields and thereby the speed in the well known manner, there is shown, for purposes of illustration, a three-phase motor having Y and delta connections. The electrical motor 17' has six terminals of which terminals 201, 202, and 203 convert the motor to a delta wound motor for driving the motor at a slow speed and terminals 204, 205, and 206 convert the motor to a Y winding for a faster speed. This motor is energized from the three-phase power terminals 207, 208, and 209.

Control of the rotation and the speed is obtained by use of four contactor relays, namely directional contactors RO' and RC' which determine the direction of rotation, and speed contactors MS and MF which control the motor speed.

For the purpose of operating the motor both clockwise and counter clockwise in order that the valve member may be moved from its open to closed and from its closed to open positions, there is provided a directional relay contactor RO' and a directional relay contactor RC' respectively as shown in Fig. 3. The directional

contactor RO' comprises a clockwise solenoid 242, which when energized, is effective to pull the armatures 243 and 245 of the relay contactor RO' into engagement with the contacts 244 and 246, respectively. As a result, terminal 207 is connected to power lead 247 by way of lead 249, contact 244 and armature 243, while terminal 208 is connected to power lead 248 by way of lead 250, contact 246, and armature 245. Connected to the terminal 209 is a power lead 251. The power leads 247, 248, and 251 are connected to a suitable source of three-phase power 252. When the armatures 243 and 245 of contactor RO' are closed, the power supply circuit is set up to cause the motor 17' to rotate in a clockwise direction so as to move the valve member from its closed to open position but such action takes place only after a speed contactor has closed to determine whether the motor runs at slow speed or at fast speed.

The directional contactor RC' is operative to rotate the motor 17' counter clockwise and does so by reversing the connections to the power supply, that is terminal 207 is connected to power lead 248 instead of power lead 247 as was the case for clockwise rotation. Likewise, terminal 208 is connected to power lead 247 instead of power lead 248 as was the case for clockwise rotation. The relay contactor RC' includes the counter clockwise solenoid 253, which upon excitation, causes its armatures 254 and 256 to be pulled into engagement with the contacts 255 and 257, respectively. As a result, terminal 208 is connected to power lead 247 by way of lead 250, lead 259, contact 255, armature 254, and lead 258, while terminal 207 is connected to power lead 248 by way of lead 261, contact 257, and armature 256.

The relay contactors MS and MF select the speed at which the motor is to run. The slow speed relay contactor MS comprises the slow speed solenoid 210 which actuates the armatures 211, 213, and 215. The solenoid 210 pulls the armatures 211, 213, and 215 into engagement with contacts 212, 214, and 216, respectively, thereby connecting motor lead 201 to terminal 207 by way of lead 217, contact 212, armature 211, and lead 218 and also connecting motor lead 202 to terminal 209-a by way of terminal 240, lead 219, contact 214, armature 213, and lead 220; and also connecting motor lead 203 to terminal 208 by way of lead 221, terminal 239, contact 216, armature 215, and lead 221-a. Thus, upon the excitation of the solenoid 210, of speed contactor MS, and solenoid 120 of directional relay contactor RO', the motor 17' is energized from the power source 252 and operates as a delta wound motor at slow speed.

Upon energization of the fast speed solenoid 222, armatures 223, 225, 227, 229, and 231 move downwardly to engage contacts 224, 226, 228, 230, and 232, respectively. This connects terminal 206 through lead 233 and lead 234 to power terminal 209, connects terminal 204 through lead 235 and lead 236 to power terminal 207, and connects terminal 205 by lead 237 and lead 238 with power terminal 208. The engagement of armatures 225 and 227 with contacts 226 and 228 shorts terminals 239 and 240 with terminal 241 thereby destroying the delta connection. Accordingly, this changes the delta connection to a Y connection and enables the motor to be operated at its fast speed. In the above manner, a provision is made for operating the motor at two speeds from the same power source.

As in the single-speed motor described above, the operation of the two-speed motor is controlled by a control system generally designated as VM'. The control system VM' is energized by the secondary winding 263 of a step-down transformer 264 of which the primary is connected to the power leads 247 and 248 by leads 264-a and 264-b. Upon closing the master switches 265, the excitation from the secondary winding 263 causes the terminals 266 and 267 to become energized.

Connected in parallel to terminals 266 and 267 is a

first circuit VO' for controlling the directional contactor RO' which governs the rotation of the motor 17' in a clockwise direction to open the valve 13 and a second circuit VC' for controlling the directional contactor RC' which governs the rotation of the motor 17' in a counter clockwise direction to close the valve 13. Also there is a third circuit RF for controlling the speed relay contactor MF which causes the motor to operate at fast speed, and a fourth circuit RS for controlling the speed relay contactor MS which causes the motor to operate at slow speed.

For rotating the motor 17' clockwise and closing the valve, the control circuit VO' is energized.

When the selector switch 301 is in engagement with contact 302, the circuit VO' will be governed by the master control system (not shown) by means of the armature 304. When the armature 304 is in engagement with contact 304-a, a circuit is completed to energize opening solenoid 242 of the relay contactor RO' from terminal 266 by way of armature 304, contact 304-a, contact 302, selector switch 301, lead 303, normally closed armature 297, contact 298, lead 304, through the solenoid 242 to terminal 267. Energization of opening solenoid 242 of the directional relay contactor RO' closes armatures 243 and 245 of the same contactor and sets up the power circuit to cause the motor 17' to run clockwise as soon as one of the speed relay contactors MF or MS is closed.

Also actuated by the solenoid 242 of the directional relay contactor RO' is the armature 268, which when closed sets up a circuit for energizing the solenoid 222 of the MF speed relay contactor or 210 of the MS speed relay contactor, through circuits RF or RS. This circuit originates from terminal 266 and terminates at terminal 272-a by way of lead 270, armature 268, contact 269, lead 272, to terminal 272-a.

Connected in parallel between terminals 272-a and 273 are two circuits RF and RS, which are operative to select whether the motor 17' runs fast or slow. The circuit RF starts from terminal 272-a and passes successively through the normally closed armature 274 of the open timer relay TO, through the contact 275, through the fast speed solenoid 222 of the speed relay contactor MF to the terminal 273. The second circuit RS starts from terminal 272-a and passes successively through the normally open armature 276 of the open timer relay TO, the contact 277, through the slow speed solenoid 210 of the speed relay contactor MS to terminal 273. When the clockwise armature 268 of the directional relay contactor RO' is closed, a selection is made as to whether the motor operates fast or slow depending upon whether open limit timer relay TO is energized or de-energized so as to close the armature 274 or close the armature 276 as more fully to be explained below.

Operatively connected to the motor by way of the gear reduction unit 22 is a shaft 75' including a cam type limit switch mechanism 154' including four cams 279, 281, 283, and 285. Cam 279 is positioned so that when the valve 13 approaches its open position *o* or slowdown point, the cam 279 forces the switch 280 to engage its contact 280-a and remains in this position even though the valve stops at the position *o*. Closing of the switch 280 completes a circuit from terminal 266 through the solenoid 291 of the open timer relay TO to terminal 267 by way of lead 289, lead 288, contact 280-a, armature 280, lead 287, armature 293, contact 294, through the solenoid 291, to terminal 267. Hence, closing of the switch 280 energizes the circuit to the solenoid 291 of the open timer relay TO. Energization of the solenoid 291 causes the armature 274 to break its connection with contact 275 and interrupt the circuit to the solenoid 222 of the speed contactor MF thereby preventing the motor 17' from operating at fast speed. Simultaneous with this action is the engagement of armature 276 with contact 277 of the open timer relay TO which action completes

a circuit for energizing solenoid 210 of the speed contactor MS thereby causing the motor 17' to run at slow speed.

The open timer relay TO is of the well known pneumatic type and comprises the solenoid 291, two normally open armatures 276 and 295, together with one normally closed armature 274. When the solenoid 291 is energized, the armatures 276 and 295 instantly engage contacts 277 and 296, respectively, and simultaneously the normally closed armature 274 disengages from contact 275. When the solenoid 291 is de-energized, there is an adjustable preset time delay caused by the pneumatic action of the relay mechanism before the through armatures resume their normal positions.

15 The cam 281 of the cam type limit switch mechanism 154 is positioned so as to move the switch 282 into engagement with the contact 282-a at approximately the point at which the valve member 13 reaches its open position *o*. Closing of the switch 282 completes a circuit from terminal 266 through the solenoid 295 of the open limit relay OR to the terminal 267 by way of lead 289, lead 296, armature 282, contact 282-a, through the solenoid 295 to terminal 267. The open limit relay OR comprises the solenoid 295 and two normally closed armatures 293 and 297. As a result of the actions described about the switch 282 causes energization of the solenoid 295 of the open limit relay OR which in turn opens the circuit through its armature 297 thereby breaking one of the parallel circuits feeding the solenoid 242 of the directional contactor RO'. This action would de-energize the solenoid 242 except for the parallel feed from terminal 266 to the solenoid 242 by way of lead 300, contact 296, armature 295a of the open timer TO, lead 299 to the solenoid 242. Energization of solenoid 295 of the open relay OR also opens its second normally closed armature 293. Disengagement of armature 293 from its contact 294 breaks the circuit from terminal 266 to the solenoid 291 of the open timer relay TO. At the end of the timing period, the three armatures 295a, 274, and 276 of the open timer relay TO will reverse their positions. This change in armature position has no effect at this time in the case of armatures 274 and 276, but the disengaging of armature 295a from contact 296 breaks the circuit from terminal 266 to the solenoid 242 of the directional contactor RO' by way of lead 300, contact 296, armature 295a, to the solenoid 242. This action results in de-energization of the solenoid 242 and causes its three armatures 243, 245, and 268 to disengage from their respective contacts. Armatures 243 and 245 disconnect 40 the power supply to the motor, causing the motor to stop, while armature 268 breaks the power supply to the solenoid 210 of the speed relay contactor MS causing it to disengage its armatures 211, 213, and 215 from their respective contacts.

45 55 The net result of the foregoing is as follows: the motor is caused to rotate in a clockwise direction at fast speed to open the valve. When the valve approaches the open position or slowdown point, the cam switch causes the motor to run at slow speed. Just before valve reaches the full open position near final stop, another cam switch de-energizes the open timer relay TO with the result that the motor will be disconnected from the power supply after a preselected time interval. Meanwhile, the valve member reaches the full open position and is against a mechanical stop preventing further movement. As a result, the fluid coupling is overloaded and slips leaving the driven end at a standstill while the motor continues to run at slow speed.

50 50 Automatic operation of the circuit VM' is effected 70 when the selector switch 301 is in engagement with the terminal 302 and the armature 304 engages the contact 304a thereby to connect the lead 303 to the terminal 266 by way of the lead 270. Actuation of the armature 304 to its closed position is accomplished by way of the operation of the master control system as explained hereto-

fore in connection with the single speed motor. Connected to the line 303 is the armature 297 of the open relay OR which remains in engagement with the contact 298 during the fast speed operation of the motor and in this position is effective to complete the circuit and energize the solenoid 242 of the directional contactor RO' which is connected thereto by way of the lead 304.

Manual operation of the opening of the valve member 13 is accomplished when the selector switch 301 engages the terminal 307 and the manual push button 308 is depressed so as to bridge the leads 309 and 310 of which the lead 310 is connected to the terminal 266 by way of the line 278.

The control circuit VC' for closing the valve is similar to the control circuit VO' for opening the valve and includes the solenoid 253 of the directional relay contactor RC' which when energized as explained above is operative to move the armatures 254 and 256 to engage the contacts 255 and 257 respectively and thereby cause the motor to rotate counter clockwise when one of the speed contactors MF or MS is energized. The solenoid 253 of directional contactor RC' also causes the armature 310 to engage the contact 311 and thereby set up a circuit RF to the solenoid 222 of the fast speed relay contactor MF or a circuit RS for the slow speed relay contactor MS, depending upon the selection made by the close timer relay TC. Since the solenoid 329 of the close timer relay TC is not energized, the normally closed armature 315 on this timer will be closed against its contact 316 and the circuit will be completed from terminal 266 to the solenoid 222 of the fast speed contactor MF by way of lead 278, lead 313, armature 310, contact 311, lead 312, terminal 314, armature 315, contact 316, lead 317 to the solenoid 222 of the fast speed contactor MF.

In starting the closing movement of the valve member 13, the control system is energized so as to operate the motor at fast speed until the valve member 13 reaches the slowdown point as it approaches the closed position c. At this time, the cam 283 of the cam type limit switch mechanism 154 is set to move the switch 284-a into engagement with the contact 284 so as to connect the terminal 266 to the solenoid 329 of the close timer relay TC by way of the lines 278 and 323, armature 284-a, contact 284, normally closed armature 320, and contact 321. Hence, when the cam switch 284 is closed, the solenoid 329 of the close timer relay TC is energized. The close timer relay TC has two normally open armatures 326 and 317 which engage contacts 327 and 318, respectively, when the solenoid 329 is energized. In addition, this timer relay TC has a normally closed armature 315, which disengages from contact 316 when the solenoid 329 is energized. All of these armatures move instantly when the solenoid is energized but there is an adjustable preset time delay before these armatures move in the opposite direction after de-energization of the solenoid 329 due to the pneumatic bellows action of the timer mechanism.

Energization of the solenoid 329 of the close timer relay TC, caused its normally closed armature 315 to be disengaged from its contact 316, breaking the circuit RF through the solenoid 222 of the fast speed contactor MF thereby discontinuing the fast speed operation of the motor. At the same time, the armature 317, of the close timer relay TC, is engaged with its contact 318 with the result that the circuit RS is completed through the solenoid 210 of the slow speed contactor MS thereby causing the motor to continue to run at slow speed. Simultaneous with the above two actions is the engagement of the normally open armature 326 of the close timer relay TC with its contact 327, thereby completing a holding circuit around the armature 331 and its contact 332, the function of which will be explained in the following paragraph.

When the valve member 13 approaches the closed posi-

tion c, the cam 285 of the cam type limit switch 154, causes the switch 286 to engage with its contact 286-a with the result that a circuit is completed from terminal 266 to the solenoid 340 of the close limit relay CR with the result that its two normally closed armatures 320 and 331 are disengaged from contacts 321 and 332, respectively. Disengagement of armature 331 from contact 332 would interrupt the power supply to the solenoid 253 of the directional contactor RC' except for the bypass circuit through armature 326 and contact 327 of the close timer relay TC as described in the preceding paragraph. Disengagement of armature 320 from contact 321 of the close limit relay CR breaks the circuit to the solenoid 329 of the close timer relay TC. As a result of the action of the pneumatic bellows in this timer, the functioning of the armatures 315, 317, and 326 of this close timer relay TC is delayed for a preset time. This permits the motor to run at slow speed driving the valve 13 to final stop in the closed position. At this valve position, the torque required to move the valve member is too great for the fluid coupling to transmit with the result that there is 100% slip in the fluid coupling thereby permitting the motor and the driven end of the fluid coupling to run at slow speed while the driven end of the coupling and the valve member are at a standstill. The torque relationship of the motor operating at slow speed and the torque characteristics of the fluid coupling are represented by the curves d and a, respectively, in Fig. 4.

At the end of the preset time interval, the three armatures 315, 317, and 326 reposition themselves. Armature 317 disengages from its contact 318 on the close timer relay TC, thereby breaking the circuit RS to the solenoid 210 of the slow speed contactor MS, while at the same time, armature 326 disengaged from its contact 327, thereby breaking the circuit to the solenoid 253 of the directional contactor RC', thereby de-energizing and stopping the motor 17.

Automatic operation of the circuit VC' is effected when the selector switch 334 is engaged with the terminal 335, and the armature 336, under the control of the master control system, engages the contact 337 such that when the armature 331 of the close relay CR is in its normal position of engagement with the contact 332, the circuit to the solenoid 253 of the directional contactor RC' is completed to the terminal 266 by way of the lines 313 and 278. In connection with the armature 336, it is to be observed that interlocking means may be provided in the master control system between the armature 336 in the circuit VC' and the armature 304 in the circuit VO' such that both the circuits are not energized simultaneously.

Manual energization of the circuit VC' for closing the valve member 13 is accomplished when the selector switch 334 engages the terminal 338 and the manual push button 340 is depressed so as to bridge the lines 341 and 311-a, the latter being connected to the terminal 266 by way of line 278.

Since the motor is not stopped instantly when the valve reaches the closed position, there is a decided advantage in having the motor run at reduced or slow speed when the valve reaches the closed or c position because there will be less shock and jar to the valve member as well as the driving mechanism. Such action is obtained through the use of a two-speed motor, because the fast speed can be used to obtain fast operation of the valve, while a change to slow speed at the slowdown point slightly ahead of the final stop will give the result that the motor will be running at slow speed when the valve reaches final stop. Because it is running at slow speed, the fluid coupling transmits far less torque to the valve driving mechanism with the result that when the valve member stops abruptly in the closed position, the fluid coupling is unable to transmit sufficient torque resulting in 100% slip in the fluid coupling and a cushioning effect.

11

ioned stoppage of the valve member while the motor continues to run.

In closing a valve and in some cases in opening a valve, the valve member comes against a positive metallic stop with the result that the valve member or disc is forced tightly against its seat to prevent leakage. It is very difficult to set a limit switch so that it will stop the motor exactly at final stop. The usual way is to set the limit to cut off the power supply somewhat ahead of final stop and trust to the inertia of the drive mechanism and motor to cause the valve to drift to final stop. This action may result in incomplete valve travel and valve leakage. The time delay circuit described above for maintaining the motor operation after the valve member 13 has reached its limit of travel is advantageous since it forces seating of the valve at either end of travel and permits the final stop limit switch to function before final stop, thereby making its adjustment easy and simple.

Variations and modifications may be made within the scope of the claims and portions of the improvements may be used without others.

What is claimed is:

1. A blast furnace stove system comprising a gaseous fluid conducting main having an inlet and an outlet end; a valve mounted in said main for controlling the flow of gaseous fluid through said inlet and outlet end, said valve comprising a valve seat and a valve member movable between closed position preventing the flow of said fluid through said main, an open position permitting the flow of said fluid through said main; actuating means for moving said valve between said open and closed positions, said actuating means including an electrical motor and a fluid coupling operatively connecting said motor with said valve member, said fluid coupling having a torque output less than the stalling torque of said motor at motor speeds equal to and less than the speed at which the motor stalling torque occurs.

2. The invention as defined in claim 1 including a control system having means for causing said motor to rotate in a direction to move said valve member to said open position and also for causing said motor to rotate in a direction to move said valve to said closed position.

3. The invention as defined in claim 2 in which said control system includes limit means for de-energizing said motor when said valve member reaches said open or closed position.

4. The invention as defined in claim 3 in which said limit means includes a relay means responsive to electric energy operative to positively interrupt the supply of electrical energy to said motor.

5. The invention as defined in claim 3 in which said control system includes time delay means for maintaining said motor energized for a selected time after said limit means are normally effective to de-energize said motor when said valve member reaches said open or closed positions.

6. The invention as defined in claim 5 in which said control system and said limit means include relay means responsive to electric energy and operative to positively interrupt the supply of electrical energy to said motor.

7. The invention as defined in claim 1 in which said motor is a two-speed motor having a first operating speed and a second speed substantially below said first operating speed.

8. The invention as defined in claim 7 in which said control system includes means for energizing a first means

12

for controlling said motor at said first operating speed during a portion of the said valve member movement and means to de-energize such said first control system and energize a second control system a selected distance 5. from said open or closed position of said valve member thereby to operate said motor at said second speed during the latter movement of said valve member.

9. The invention as defined in claim 7 in which said control system includes control means for causing said 10 motor to rotate in a direction to move said valve member to said open position and also for causing said motor to rotate in a direction to move said valve to said closed position.

10. The invention as defined in claim 9 in which said 15 control means includes means for energizing a first control system for controlling said motor at said first operating speed during a portion of the valve member movement from one position to another, and means to de-energize said first control system and energize a second 20 control system a selected distance from the final limit of travel of said valve member thereby to operate motor at second speed during another portion of the movement of said valve member.

11. The invention as defined in claim 10 in which said 25 control system includes limit means for de-energizing said motor when said valve member reaches said open or closed positions.

12. The invention as defined in claim 8 in which said 30 control system includes a preset limit means for initiating the change from said first operating speed to said second operating speed at a predetermined distance from said open or closed position, and a second preset limit means for de-energizing said motor when said valve member reaches said open or closed position.

13. The invention as defined in claim 10 in which said 35 control system includes a first preset limit means for initiating the change from said first operating speed to said second operating speed at a predetermined distance from said open or closed positions, and a second preset limit means for de-energizing said motor when said valve member reaches said open or closed position.

14. The invention as defined in claim 10 in which said 40 control system includes time delay means for maintaining said motor energized for a selected time after said limit means are normally effective to de-energize said motor when said valve member reaches said open or closed positions.

15. The invention as defined in claim 13 in which said 45 control means and said limit means includes a relay means responsive to electrical energy operative to positively interrupt the supply of electrical energy to said motor.

16. The invention as defined in claim 13 in which the 50 control system includes a time delay means for maintaining said motor energized for a selected time after said limit means are normally effective to de-energize said motor when said valve member reaches said open or closed positions.
